(57) **CLAIM**

We claim the ornamental design for a faucet, as shown and described.

DESCRIPTION

FIG. 1 is a top, front, right perspective view of a faucet in accordance with our design;

FIG. 2 is a right side elevational view thereof, with the left side elevational view being a mirror image thereof;

FIG. 3 is a front elevational view thereof;

FIG. 4 is a rear elevational view thereof;

FIG. 5 is a top plan view thereof;

FIG. 6 is a top, front, right perspective view of a portion of the faucet shown in FIGS. 1-5;

FIG. 7 is right side elevational view of the portion of the faucet shown in FIG. 6, with the left side elevational view being a mirror image thereof;

FIG. 8 is a front elevational view thereof; and,

FIG. 9 is a top plan view thereof.
